UNITED STATES PATENT OFFICE.

FREDERICK K. VIAL, OF LA GRANGE, ILLINOIS.

SAND-BLAST MECHANISM.

No. 839,342.

Specification of Letters Patent.

Patented Dec. 25, 1906.

Application filed October 26, 1905. Serial No. 284,557.

To all whom it may concern:

Be it known that I, FREDERICK K. VIAL, a citizen of the United States, residing in La Grange, county of Cook, and State of Illinois, have invented certain new and useful Improvements in Sand-Blast Mechanisms, of which the following is a specification.

My invention relates to that class of sand-blast mechanisms having a suitable receptacle for receiving the article to be operated upon and provided with means for introducing a plurality of currents or blasts so that they strike opposite portions or sides of the article to be operated upon.

The principal object of this invention is to provide a simple, economical, and efficient sand-blast mechanism adapted to be used for the purpose of cleaning metallic articles, such as car-wheels and the like.

A further object is to provide a sand-blast mechanism adapted to subject the article to be operated upon to a plurality of currents or blasts of air and sand, so as to enable the article operated upon to be cleaned on opposite sides without the necessity of removing it from the blast-box or reversing it laterally during the process of being cleaned.

Other and further objects of the invention will appear from an examination of the drawings and the following description and claims.

The invention consists in a sand-blast mechanism having a suitable receptacle or blast-box for containing the article to be operated upon and provided with means for introducing a plurality of currents or blasts of air containing sand into the blast-box at different points and on opposite sides of such article, whereby the article may be cleaned on both sides without being removed and laterally reversed.

It consists, further and finally, in the features, combinations, and details of construction hereinafter described and claimed.

In the accompanying drawings, Figure 1 is a diagrammatic view of a sand-blast mechanism constructed in accordance with my improvements; Fig. 2, a side elevation of the blast box or receptacle for containing the articles to be operated upon; Fig. 3, a transverse sectional elevation taken through the center of the blast-box; Fig. 4, a central sectional elevation taken on line 4 of Fig. 3 looking in the direction of the arrow, showing the mechanism for supporting the car-wheels in position to be operated upon and

for discharging the same from the blast-box; Fig. 5, a sectional plan view of the blast-box and the mechanism for supporting and rotating the wheels to be operated upon, taken on line 5 of Fig. 4; Fig. 6, a plan view in detail taken on line 6 of Fig. 2, showing the blast-pipe nozzles and connections; Fig. 7, a detail sectional elevation of the sand receiving and feeding hopper, and Fig. 8 a sectional plan view taken on line 8 of Fig. 7, showing the blast-pipes in longitudinal section.

In constructing a sand-blast mechanism in accordance with my improvements I provide a blast box or receptacle for containing the articles, such as car-wheels, to be operated upon. This blast-box is preferably formed of metallic side portions *a* and *b* and a top portion *c*, forming a chamber of the desired dimensions, which is closed at its opposite sides by vertical sliding doors *d*, adapted to be raised to permit the car-wheels to be rolled into and out of the blast-box and lowered, so as to form a closed chamber while the articles to be operated upon are being treated. A hopper *e*, having a screen *f* mounted therein and forming a sand-containing chamber *g* beneath such screen, is provided for receiving and feeding the sand into position to be introduced into the blast box by means of compressed air in such manner as to subject the car-wheels or other articles to be operated upon to the action of the sand-blast. This hopper may be of any ordinary and well-known type and is provided with an inlet-valve *h*, which is vertically removable by means of a hand-lever *i*, articulately connected with the valve-stem *j* by means of a suitable pivot *k*. The valve-stem is mounted in bearings *l* and *m* and the lever in a support *n*. A counterweight *o* is adapted to hold the valve normally in closed position and permit it to be pressed downward into open position by the operation of the hand-lever. A chamber *p*, formed by a casing *q*, is provided beneath the hopper being closed, so as to enable the sand when admitted thereto to be forced by means of air under pressure introduced through a pipe *r* into sand-pipes *s*, which lead into the branch pipes *t*. A plurality of these branch pipes lead to one side of the blast-box and are provided with nozzles which extend through the side portion thereof, and a plurality of the branch blast-pipes extend to and are provided with nozzles which extend into the opposite sides of the blast-box, as shown in

Figs. 1 and 6. A plurality of jets or currents of air containing sand may thus be introduced simultaneously on opposite sides of the blast-box, so as to subject both sides of the article simultaneously to the action of the blast. By this means a car-wheel may be introduced into the blast box or receptacle and thoroughly cleaned without being removed for the purpose of reversing its position and in less than one-half the time ordinarily required. Each of the blast-pipes is provided with a nozzle *u*, which extends through a perforation *v* in a laterally-projecting portion *w* of the side of the blast-box and through similar perforations *y* in suitable bearing members 2. These perforated supporting members form the sockets of ball-and-socket joints, and each nozzle is provided with a ball member 3, which is seated in such socket members. An air-tight joint is thus formed between the nozzles or blast-pipes and their supports.

The branch pipes may be made of flexible material, and the nozzles thus permit the direction of the sand-blast to be changed by adjusting the nozzles to point in the desired direction. The nozzles are each provided with an end tip 4, secured thereto by means of a set-screw 5, such tips having flaring or enlarged discharge-passages 6, which permit the blast to spread to the desired extent as it comes into contact with the wheel or other article to be operated upon.

The blast mechanism here shown is particularly adapted to be used for cleaning car-wheels. It is desirable to provide suitable means for introducing the wheels into the blast-box, supporting them therein, and discharging them therefrom, and also suitable means for keeping the wheels in rotation while they are being operated upon. To accomplish this, a plurality of conical supporting-rolls 7, having peripheral grooves 8 for receiving the flanges of the car-wheels to be operated upon, are mounted in the blast-box with their axial centers arranged transversely of such box or receptacle. These wheels are mounted upon shafts 9 and 10, which are rotatably mounted in bearings 11 and 12. The shaft 9 is provided with a sprocket 13 and the shaft 10 with a sprocket 14, and a sprocket-chain 15 is mounted upon and connects such sprocket-wheels, and thereby the shafts, so that they rotate together. A driving sprocket-wheel 16 is also mounted upon the shaft 9 and is adapted to be connected with a suitable source of power in any ordinary and well-known manner. A supporting-bracket 17 is mounted upon an I-beam 18 on one side of the blast-box, forming a support for the corresponding ends of the above-described shafts and their bearings, and a similar supporting-bracket 19 is mounted upon an I-beam 20 on the opposite side of the blast-box, forming a support for the opposite ends

of the shafts and their bearings, as shown in Fig. 3.

A pair of track-rails 21 extend into the receiving side of the blast-box in such position that their inner ends are on opposite sides of the peripheral groove of the adjacent supporting-roll and their upper bearing-surfaces preferably almost on the same plane or slightly below the upper supporting-surface of the adjacent grooved roll. These rails have a space therebetween of substantially the same width as the groove in the adjacent roll and are adapted to permit the flanges 22 of the car-wheels 23 to be operated upon to pass between such rails and be guided thereby into the peripheral grooves of the supporting-rolls. Similar tracks 24 extend from the opposite supporting-roll outward through the discharge side of the blast-box beneath the vertically-movable door and are adapted to guide the car-wheel, with its flange portion, between such rails as it is discharged from the blast-box after being treated. While the car-wheel is in the blast-box it rests upon the supporting-rolls 7, already described, with its flange in the peripheral grooves in such rolls. By keeping the rolls in rotation while the blast is being introduced the wheel may be kept constantly in rotation and subjected to the action of the blast at all points and on opposite sides simultaneously.

In order to provide suitable means for discharging the wheel from the blast-box, a rock-shaft 25 is mounted transversely of such box in suitable bearings in the brackets 100 17 and 19, already described, and an operating-lever 26 is secured to such rock-shaft. The rock-shaft is provided with a curved crank-arm 27, having its outer swinging end 28 intermediate the end of one of the rails 21 and the adjacent supporting-roll. The rock-shaft is mounted intermediate the supporting-rolls, as shown in Figs. 4 and 6, and substantially on a plane with the axial center thereof, so that when the operating-lever is moved in the direction to raise the swinging end of the crank-arm the car-wheel will be discharged from the rolls onto the discharging-rails. Any desired number of wheels may be introduced and discharged consecutively in a similar manner by simply raising the doors and rolling such wheels in manually and out by means of the rock-shaft and lever mechanism.

To permit the doors to be readily raised and lowered, a counterweight 29 is connected therewith by means of the flexible elements 30, which may be in the form of metallic cords mounted upon sheave-pulleys 31, 32, 33, and 34, supported above the doors upon a suitable fixed frame portion 35 by means of brackets 36. The lower ends of these flexible elements are provided with loops 37, by means of which they are attached to the upper ends of the vertically-movable doors, 130

and the opposite ends are connected with the counterweight above described by means of a link 38 and an eyebolt or link 39. An operating-cord 40 is attached to the lower end of the eyebolt or link and is adapted to extend to any desired point within convenient reach of the operator.

A compressed-air pipe 41 communicates with the converging ends of the sand-blast pipes 4 and with a source of compressed air, such pipe being provided with a controlling-valve 42, having operating-levers 43, by means of which the air-passage may be opened and closed, as desired. Air under pressure may be thus admitted to the blast-pipes to form blasts which will force the sand into contact with the wheel or other article to be operated upon.

An outlet-pipe 44 leads from the upper portion of the blast-box or operating-chamber downward to a dump box or receptacle 45, having a discharge-opening. This receptacle is adapted to receive the heavier particles of that portion of sand and the refuse removed from the wheel which passes through the pipe 44, and a discharge-pipe 46 leads from such box upward into a discharge or settling chamber 47, which is provided with downwardly-extending baffles 48 and upwardly-extending baffles 49, arranged at suitable intervals in alternate relation, so as to divert the current of air discharged from the discharge-pipe 46 upward and downward until the dust is permitted to settle in the receptacle. An air-discharge pipe 50 is provided, in which is mounted a suction-fan 51 for forcing the air from the settling-chamber after the dust has settled. The chamber or receptacle 47 is provided with a hopper-bottom portion 52, the inclined portions of which extend downward and toward the center of the hopper at an incline from the opposite sides thereof, so as to convey the dust to the discharge-opening in the bottom portion or chute 53. A pipe 54 leads from the bottom of a sand receiving and discharge box 55 at the bottom of the blast-box or operating-chamber and into the discharge-pipe 46, so that sand is forced from such box into the discharge-pipe and from such pipe into the settling chamber or receptacle above described. When the exhaust-air with the sand and other particles contained therein reaches this chamber from the blast-box, the heavier particles of sand are fit to be used over again, and the lighter particles in the form of dust, while not of any further use, should be permitted to settle before leaving the chamber. This protects the health of the operator. The heavier particles of sand come in contact with the first upwardly-extending baffle 49 and are discharged through a pipe 56 into a separating box or chute 57, having an inclined screen 58 and beneath such screen another similarly-inclined screen

of finer mesh. The screen 59 extends over a discharging-hopper portion 60 and the screen 58 over the hopper portion 61, the box being provided with an inclined discharge 62 beyond such main hopper portion for discharging into a receptacle 63 the material which is too coarse to pass through either screen. The main hopper portion 61 has a discharge-chute 64, which leads to the initial sand receiving and feeding hopper 65, already described. By this means it will be seen that the sand or other material which will not pass through the screen 58 is finally discharged into the receptacle 63 and that the material which will pass through such screen, but not through the screen 59, is emptied into the initial sand receiving and feeding hopper to be used over again, while the particles of material which are so fine as to pass through the screen 59 are discharged through a chute or pipe 66 onto a suitable receptacle or dump for receiving the waste material.

I claim—

1. In a mechanism of the class described, the combination of a receptacle forming a chamber for containing a car wheel or wheels to be operated upon, blast-pipes leading to such receptacle and communicating with the chamber formed thereby, a sand receiving and feeding hopper provided with passages leading to such blast-pipes, a compressed-air pipe communicating with the blast-pipes and adapted to be connected with a source of compressed air, an outlet-pipe leading from the operating-chamber of such receptacle, a settling-chamber with which such outlet-pipe communicates, and a hopper-bottom for such settling-chamber provided with openings for discharging material therethrough.

2. In a mechanism of the class described, the combination of a receptacle forming a chamber for containing a car wheel or wheels to be operated upon, blast-pipes leading to such receptacle, a sand receiving and feeding hopper provided with passages leading to such blast-pipes, a compressed-air pipe communicating with the blast-pipes and adapted to be connected with a source of compressed air, an outlet-pipe leading from the operating-chamber of such receptacle, a settling-chamber with which such outlet-pipe communicates, a hopper-bottom for such settling-chamber provided with openings for discharging material therethrough, and means for conveying material from one of such openings back to the sand receiving and feeding hopper.

3. In a mechanism of the class described, the combination of a blast-box, blast-pipes leading to opposite sides thereof, a sand receiving and feeding hopper provided with passages communicating with such blast-pipes for conducting sand thereto, air-pipe mechanism connected with the blast-pipes and communicating with a suitable source

- of air under pressure, an outlet-pipe leading from the blast-box, and means for conducting material from such outlet-pipe back to the sand receiving and feeding hopper.
5. In a mechanism of the class described, the combination of a blast-box, blast-pipes leading thereto, a sand receiving and feeding hopper provided with passages communicating with such blast-pipes for conducting sand thereto, air-pipe mechanism connected with the blast-pipes and communicating with a suitable source of air under pressure, an outlet-pipe leading from the upper portion of the blast-box, and a pipe leading from the bottom of the blast-box into the outlet-pipe.
10. In a mechanism of the class described, the combination of a blast-box, blast-pipes leading thereto, a sand receiving and feeding hopper provided with passages communicating with such blast-pipes for conducting sand thereto, air-pipe mechanism connected with the blast-pipes and communicating with a suitable source of air under pressure, an outlet-pipe leading from the blast-box, a settling-chamber with which such outlet-pipe communicates provided with a discharge-passage, and a plurality of baffles mounted in such settling-chamber.
15. In a mechanism of the class described, the combination of a blast-box, blast-pipes leading thereto, a sand receiving and feeding hopper provided with passages communicating with such blast-pipes for conducting sand thereto, air-pipe mechanism connected with the blast-pipes and communicating with a suitable source of air under pressure, an outlet-pipe leading from the blast-box, a settling-chamber with which such outlet-pipe communicates provided with a discharge-passage, and a plurality of baffles mounted in such settling-chamber.
20. In a mechanism of the class described, the combination of a blast-box, blast-pipes leading thereto, a sand receiving and feeding hopper provided with passages communicating with such blast-pipes for conducting sand thereto, air-pipe mechanism connected with the blast-pipes and communicating with a suitable source of air under pressure, an outlet-pipe leading from the blast-box, a settling-chamber with which such outlet-pipe communicates provided with a discharge-passage, and a plurality of baffles mounted in such settling-chamber.
25. In a mechanism of the class described, the combination of a blast-box, blast-pipes leading thereto, a sand receiving and feeding hopper provided with passages communicating with such blast-pipes for conducting sand thereto, air-pipe mechanism connected with the blast-pipes and communicating with a suitable source of air under pressure, an outlet-pipe leading from the blast-box, a settling-chamber with which such outlet-pipe communicates provided with a discharge-passage, and a plurality of baffles mounted in such settling-chamber.
30. In a mechanism of the class described, the combination of a blast-box, blast-pipes leading thereto, a sand receiving and feeding hopper provided with passages communicating with such blast-pipes for conducting sand thereto, air-pipe mechanism connected with the blast-pipes and communicating with a suitable source of air under pressure, an outlet-pipe leading from the blast-box, and communicating with the sand receiving and feeding hopper, and an outlet-pipe leading from the bottom of the blast-box into such outlet-pipe.
35. In a mechanism of the class described, the combination of a blast-box, blast-pipes leading thereto, a sand receiving and feeding hopper provided with passages communicating with such blast-pipes for conducting sand thereto, air-pipe mechanism connected with the blast-pipes and communicating with a suitable source of air under pressure, an outlet-pipe leading from the blast-box, and communicating with the sand receiving and feeding hopper, and an outlet-pipe leading from the bottom of the blast-box into such outlet-pipe.
40. In a mechanism of the class described, the combination of a blast-box, blast-pipes leading thereto, a sand receiving and feeding hopper provided with passages communicating with such blast-pipes for conducting sand thereto, air-pipe mechanism connected with the blast-pipes and communicating with a suitable source of air under pressure, an outlet-pipe leading from the blast-box, and communicating with the sand receiving and feeding hopper, and an outlet-pipe leading from the bottom of the blast-box into such outlet-pipe.
45. In a mechanism of the class described, the combination of a blast-box, blast-pipes leading thereto, a sand receiving and feeding hopper provided with passages communicating with such blast-pipes for conducting sand thereto, air-pipe mechanism connected with the blast-pipes and communicating with a suitable source of air under pressure, an outlet-pipe leading from the blast-box, a settling-chamber with which such outlet-pipe communicates provided with a discharge-passage, a plurality of baffles mounted in such settling-chamber, and a hopper-bottom forming inclined bottom portions for such settling-chamber and provided with a discharge-opening for discharging material therethrough.
50. In a mechanism of the class described, the combination of a blast-box, blast-pipes leading thereto, a sand receiving and feeding hopper provided with passages communicating with such blast-pipes for conducting sand thereto, air-pipe mechanism connected with the blast-pipes and communicating with a suitable source of air under pressure, an outlet-pipe leading from the blast-box, a settling-chamber with which such outlet-pipe communicates provided with a discharge-passage, a plurality of baffles mounted in such settling-chamber, and a hopper-bottom forming inclined bottom portions for such settling-chamber and provided with a discharge-opening for discharging material therethrough.
55. In a mechanism of the class described, the combination of a blast-box, blast-pipes leading thereto, a sand receiving and feeding hopper provided with passages communicating with such blast-pipes for conducting sand thereto, air-pipe mechanism connected with the blast-pipes and communicating with a suitable source of air under pressure, an outlet-pipe leading from the blast-box, a settling-chamber with which such outlet-pipe communicates provided with a discharge-passage, a chute for receiving the material from such outlet-pipe provided with a passage communicating with the sand receiving and feeding hopper and with a passage leading away from such hopper, and a screen mounted in such chute for separating the material to be turned to the sand receiving and feeding hopper from the material to be discharged outside thereof.

Correction in Letters Patent No. 839,342.

It is hereby certified that in Letters Patent No. 839,342, granted December 25, 1906, upon the application of Frederick K. Vial, of La Grange, Illinois, for an improvement in "Sand-Blast Mechanisms," an error occurs in the printed specification requiring correction, as follows: In line 77, page 4, the word "turned" should read *returned*; and that the said Letters Patent should be read with this correction therein that the same may conform to the record of the case in the Patent Office.

Signed and sealed this 15th day of January, A. D., 1907.

[SEAL.]

F. I. ALLEN,
Commissioner of Patents.

- of air under pressure, an outlet-pipe leading from the blast-box, and means for conducting material from such outlet-pipe back to the sand receiving and feeding hopper.
5. In a mechanism of the class described, the combination of a blast-box, blast-pipes leading thereto, a sand receiving and feeding hopper provided with passages communicating with such blast-pipes for conducting sand thereto, air-pipe mechanism connected with the blast-pipes and communicating with a suitable source of air under pressure, an outlet-pipe leading from the upper portion of the blast-box, and a pipe leading from the bottom of the blast-box into the outlet-pipe.
10. In a mechanism of the class described, the combination of a blast-box, blast-pipes leading thereto, a sand receiving and feeding hopper provided with passages communicating with such blast-pipes for conducting sand thereto, air-pipe mechanism connected with the blast-pipes and communicating with a suitable source of air under pressure, an outlet-pipe leading from the blast-box, a settling-chamber with which such outlet-pipe communicates provided with a discharge-passage, and a plurality of baffles mounted in such settling-chamber.
15. In a mechanism of the class described, the combination of a blast-box, blast-pipes leading thereto, a sand receiving and feeding hopper provided with passages communicating with such blast-pipes for conducting sand thereto, air-pipe mechanism connected with the blast-pipes and communicating with a suitable source of air under pressure, an outlet-pipe leading from the blast-box, a settling-chamber with which such outlet-pipe communicates provided with a discharge-passage, and a plurality of baffles mounted in such settling-chamber.
20. In a mechanism of the class described, the combination of a blast-box, blast-pipes leading thereto, a sand receiving and feeding hopper provided with passages communicating with such blast-pipes for conducting sand thereto, air-pipe mechanism connected with the blast-pipes and communicating with a suitable source of air under pressure, an outlet-pipe leading from the blast-box, a settling-chamber with which such outlet-pipe communicates provided with a discharge-passage, and a plurality of baffles mounted in such settling-chamber.
25. In a mechanism of the class described, the combination of a blast-box, blast-pipes leading thereto, a sand receiving and feeding hopper provided with passages communicating with such blast-pipes for conducting sand thereto, air-pipe mechanism connected with the blast-pipes and communicating with a suitable source of air under pressure, an outlet-pipe leading from the blast-box, a settling-chamber with which such outlet-pipe communicates provided with a discharge-passage, and a plurality of baffles mounted in such settling-chamber.
30. In a mechanism of the class described, the combination of a blast-box, blast-pipes leading thereto, a sand receiving and feeding hopper provided with passages communicating with such blast-pipes for conducting sand thereto, air-pipe mechanism connected with the blast-pipes and communicating with a suitable source of air under pressure, an outlet-pipe leading from the blast-box, and communicating with the sand receiving and feeding hopper, and an outlet-pipe leading from the bottom of the blast-box into such outlet-pipe.
35. In a mechanism of the class described, the combination of a blast-box, blast-pipes leading thereto, a sand receiving and feeding hopper provided with passages communicating with such blast-pipes for conducting sand thereto, air-pipe mechanism connected with the blast-pipes and communicating with a suitable source of air under pressure, an outlet-pipe leading from the blast-box, and communicating with the sand receiving and feeding hopper, and an outlet-pipe leading from the bottom of the blast-box into such outlet-pipe.
40. In a mechanism of the class described, the combination of a blast-box, blast-pipes leading thereto, a sand receiving and feeding hopper provided with passages communicating with such blast-pipes for conducting sand thereto, air-pipe mechanism connected with the blast-pipes and communicating with a suitable source of air under pressure, an outlet-pipe leading from the blast-box, and communicating with the sand receiving and feeding hopper, and an outlet-pipe leading from the bottom of the blast-box into such outlet-pipe.
45. In a mechanism of the class described, the combination of a blast-box, blast-pipes leading thereto, a sand receiving and feeding hopper provided with passages communicating with such blast-pipes for conducting sand thereto, air-pipe mechanism connected with the blast-pipes and communicating with a suitable source of air under pressure, an outlet-pipe leading from the blast-box, a settling-chamber with which such outlet-pipe communicates provided with a discharge-passage, a plurality of baffles mounted in such settling-chamber, and a hopper-bottom forming inclined bottom portions for such settling-chamber and provided with a discharge-opening for discharging material therethrough.
50. In a mechanism of the class described, the combination of a blast-box, blast-pipes leading thereto, a sand receiving and feeding hopper provided with passages communicating with such blast-pipes for conducting sand thereto, air-pipe mechanism connected with the blast-pipes and communicating with a suitable source of air under pressure, an outlet-pipe leading from the blast-box, a settling-chamber with which such outlet-pipe communicates provided with a discharge-passage, a plurality of baffles mounted in such settling-chamber, and a hopper-bottom forming inclined bottom portions for such settling-chamber and provided with a discharge-opening for discharging material therethrough.
55. In a mechanism of the class described, the combination of a blast-box, blast-pipes leading thereto, a sand receiving and feeding hopper provided with passages communicating with such blast-pipes for conducting sand thereto, air-pipe mechanism connected with the blast-pipes and communicating with a suitable source of air under pressure, an outlet-pipe leading from the blast-box, a settling-chamber with which such outlet-pipe communicates provided with a discharge-passage, a chute for receiving the material from such outlet-pipe provided with a passage communicating with the sand receiving and feeding hopper and with a passage leading away from such hopper, and a screen mounted in such chute for separating the material to be turned to the sand receiving and feeding hopper from the material to be discharged outside thereof.
